CONTROL DEVICE

Edgar H. Ayers, Schenectady, N. Y., assignor to
 General Electric Company, a corporation of
 New York

Application April 30, 1942, Serial No. 441,148

7 Claims. (Cl. 200—83)

My invention relates to control devices, more particularly to temperature responsive control devices for controlling the circuit of a driving motor such as in an electric refrigerator and has for its object a simple, reliable and low cost control device.

In carrying out my invention in one form, I arrange the bellows spring in direct opposition to the temperature responsive bellows with a slidably mounted switch operating member between them. This operating member has a projection extending to one side which engages and operates a switch arm, snap action being obtained by means of a permanent magnet.

In order to provide for a desirably small temperature differential in the opening and closing movement of the switch arm, I provide a stop against which normally rests the side of the operating member opposite the operating projection, and I also arrange the seat for the spring slightly higher on this side so that the operating member is normally held against the projection and the operating member thereby normally has a pivotal movement in the operation of the switch arm.

For a more complete understanding of my invention, reference should be had to the accompanying drawing in which Fig. 1 is a side view of a control device for electric refrigerators embodying my invention; Fig. 2 is an end view of Fig. 1; Fig. 3 is a view similar to Fig. 1 but with the enclosing casing mainly in section so as to show the operating parts; Fig. 4 is a view in section along the line 4—4 of Fig. 3 but omitting the cover; Fig. 5 is a view similar to Fig. 2 but with the cover in section; Fig. 6 is a fragmentary view showing the supporting frame for the bellows operating parts; while Figs. 7 and 8 are views showing details of construction.

Referring to the drawing, in one form of my invention I provide a temperature responsive expandible bellows 10 which is cylindrical with peripheral corrugations and a helical loading spring 11 in opposition to the bellows having its center line coincident with the center line of the bellows 10. Between the spring and the bellows is an operating member 12 whose lower side forms a seat for the upper end of the bellows and whose upper side is provided with a circular recess forming a seat for the spring 11. A laterally extending projection 13 on the operating member 12 engages and operates a spring switch arm 14, snap action being obtained by a small permanent magnet 15 and an armature 16 carried by the switch arm.

As shown, the various parts are mounted on a supporting base 17 which is provided with a cylindrical recess 18 for the bellows 10, this recess being deep enough so that the bellows projects only a short distance above the upper surface of the support 17 where the bellows engages the operating member 12.

Secured to the upper surface of the support 17 is an inverted U-shaped supporting member 19 made of a suitable metal such as steel, the ends of its legs being secured to the support 17 by screws 20 and 21. One leg of the member 19 is provided with a vertically extending slot 22 into which extends loosely a projection 23 on the support 12. The other leg of the support 19 is provided with a short section 24 extending vertically and of reduced width which is embraced loosely by the operating projection 13 and a shorter positioning projection 25 on the operating member 12. Thus the operating member 12 is free to move upward, as seen in the drawing, until the projection 23 engages the upper wall of the slot 22 and the projections 13 and 25 engage the shoulders marking the upper termination of the reduced portion 24. The member 12 has sufficient freedom of movement on the support 19 in a downward direction to assure the operation of the switch arm 14.

As shown in Fig. 6, the inverted U-shaped supporting member 19 has secured to it a second U-shaped supporting member 26, the two U-shaped members 19 and 26 forming together a rectangular metallic frame or support. The ends of the two members are turned outward and secured together by welded joints 27 and 28, these outwardly extending portions forming projections which are secured to the support 17 by the screws 20 and 21 whereby the rectangular frame is secured to the support.

These two members 19 and 26 are shown clearly in Fig. 6 and form a support for the bellows 10, operating member 12, spring 11 and other parts directly associated therewith. Also, as shown in Fig. 3, the member 26 extends downward into the recess or inverted cap enclosure 18 on the lower side of the support 17. As shown, the tube 29 leading to the bellows is secured by a soldered joint 30 to the lower end of the member 26, the tube passing through a central aperture in the member. It will be understood that the tube 29 extends to the part whose temperature is thereby controlled, such as the evaporator of the refrigerator, where the end of the tube is sealed, and that the tube and bellows form a closed system in which is contained a quantity

of fluid or gas whose pressure varies with its temperature whereby the bellows is caused to expand and contract with changes in temperature so as to operate the member 12.

The pressure of the spring 11 applied to the operating member 12 can be adjusted by turning a knob 31 having a center line coincident with the center line of the spring 11 and rotatably mounted in the upper or base portion of the support 19. At its lower end this rod carries a threaded portion 32 which is in screw-threaded engagement with a metal seat 33 for the upper end of the spring 11. This seat 33 is held against turning by a pair of projections 34 which embrace one arm of the member 19, as seen in Fig. 5.

For the purpose of latching the contact arm 14 in its open circuit position, a cam projection 35 is provided on the lower face of the knob 31. It is contemplated that the threaded portion 32 will have sufficient thread pitch to give the desired adjustment in the pressure of the spring 11 in less than one revolution of the knob. Also, as shown, the threads will be such as to move the seat 33 downward and compress the spring when the knob is turned counterclockwise, looking down on Fig. 3. Thus, as the knob is turned in a counterclockwise direction, the cam 35 just before the knob reaches its extreme counterclockwise position engages the upper end of a push rod 36, the lower end of which engages the switch arm 14. A small amount of continued rotation of the knob causes the cam to force this rod 36 downward, thereby moving the arm 14 downward to its open circuit position where it is held as long as the knob remains in this position. This provides for the stopping of the refrigerator as desired, for example, to allow the evaporator to defrost itself.

As shown, the push rod 36, in order to secure it in place, is provided with a short portion 37 on its lower end of reduced size, which portion extends through an aperture 38 (Fig. 4) in the switch arm. As shown also, the push rod is a strap having a rectangular cross-section made of an electrically insulating material. Its upper end slides in a slot 39 in a projection on the upper end of the support 19. The hole 38 in the arm 14 for the push rod 36 is also rectangular in outline and positioned directly below the slot 39 with its longer dimension at right angles with the slot 39. Thus the push rod is put in place by inserting its lower end in the aperture 38 until the reduced portion 37 is in the aperture, then turning the push rod 90 degrees about its longitudinal center line and slipping it sidewise into the slot 39. The upper end of the push rod 36 is further held by the cover 40 which encloses the operating parts and also, as shown, the upper end of the support 11, this cover being provided with an aperture through which the rod 36 extends loosely in the path of the cam 35.

As shown in Fig. 4, the spring contact arm 14 is L-shaped, i. e., it extends from its free end along one dimension of the support 17 and then extends across the end of the support 17 to the support 41 for the switch arm. This support 41 extends downward into engagement with the lower side of the base 17 where it is secured to the base by suitable screws (not shown), this portion of the support 41 on the bottom of the base constituting a connection terminal for the switch arm. By thus extending the switch arm 14 along two sides of the base, the advantage of increased length and hence flexibility is obtained,

the dimensions of the base being maintained as small as possible.

A stationary spring switch arm 42 carries a stationary contact 43 in position to be engaged by the contact on the end of the arm 14. This arm 42 is just above the arm 14, as seen in Fig. 3. Its fixed end is secured to a bracket or support 44 secured to the lower side of the base by means of screws 45, this support 44 also constituting a connection terminal for the stationary contact arm. Preferably the contact arm is electrically secured to the support 44 by a spot welded joint 46. For adjustment of the arm 42 the support 44 extends a short distance along the arm 42 but at an angle therewith, and carries an adjustment screw 47 by means of which the position of the arm 42 and of the stationary contact 43 can be adjusted as desired with relation to the movable contact.

This adjustment by the screw 47 varies primarily the temperature differential between the closed and open positions. It varies the cold temperature at which the switch is opened without affecting the higher temperature at which the switch is reclosed. In other words, with the contact 43 in a raised position a lower temperature is required to snap the movable contact arm 14 to its open position.

A screw 48 is provided in the base in position to engage the movable end of the contact arm in its open circuit position. This adjustment changes the high temperature at which the contact arm is moved to its closed position.

During normal operation of the contact arm 14 between its closed and open circuit positions by the bellows whereby the refrigerator is maintained at a predetermined temperature, the projection 23 on the operating member 12 rests continuously on the lower edge of the slot 22 which edge forms a stop. In moving the switch arm, the operating projection 13 on the other end therefore moves about this stop, constituted by the lower edge of the opening 22, as a pivot. Of course in the event of an extremely high bellows temperature as when the refrigerator is shut down by permanently disconnecting it from the electric circuit, the operating member 12 is forced bodily upward against the spring 11, the projection 23 moving to the upper end of the slot 22.

This pivotal movement of the slidable member 12 in operating the contact arm provides the smallest possible temperature differential between the open and closed circuit positions of the switch arm 14. It is essential in the effecting of this pivotal operation that the force of the spring 11 be applied to the operating member 12 at a point between the point of application of the bellows force and the stop formed by the lower edge of the aperture 22. The spring 11 and the bellows 10 are shown as in axial alignment, that is, having a common center line, but because of manufacturing inaccuracies in the spring for quantity production, the spring force will not be applied evenly to the operating member 12, and therefore the spring force ordinarily will not directly oppose the bellows force. To assure the application of the spring force between the bellows force and the stop, the corresponding side 49 of the spring seat on the operating member is made higher than the other side, this high side, in other words, being adjacent the projection 23. Moreover, in the assembly of the device, the spring 11 is preferably rotated about its longitudinal center line on the operating

member so as to bring the high side of the spring on the high point 49 of the seat. It will be understood, of course, that the high side of the spring is, in reality, the lowermost side of the spring as seen in the drawing.

While I have shown a particular embodiment of my invention, it will be understood, of course, that I do not wish to be limited thereto, since many modifications may be made and I therefore contemplate by the appended claims to cover any such modifications as fall within the true spirit and scope of my invention.

What I claim as new and desire to secure by Letters Patent of the United States, is:

1. A control device comprising a rectangular metal frame, an operating member extending across said frame, means securing said operating member to said frame for limited sidewise sliding movement with relation to said frame, a bellows temperature responsive operating device mounted between one side of said operating member and one end of said frame, a compression spring between the other side of said operating member and the other end of said frame, said frame forming a support for said parts and holding said parts together against the force of said spring, means for adjusting the force applied by said spring to said operating member, and switching means outside of said frame operated by said operating member.

2. A control device comprising a base, a frame secured to said base, a temperature responsive bellows in said frame, an operating member extending across said frame having its ends slidably mounted in said frame, a spring in said frame normally holding said operating member against said bellows, said frame forming a support for said parts and holding said parts together against the force of said spring, means including a screw mounted on said frame for adjusting the force applied by said spring to said operating member, a flexible contact arm outside of said frame mounted on said base adjacent said supporting frame, an operating projection on one side of said operating member engaging said contact arm so that said contact arm is moved by said bellows in response to changes in temperature, a projection on the opposite side of said operating member, and a stop on said frame for said second projection about which said operating member pivots in operating said contact arm.

3. A control device comprising a base provided with a recess, a rectangular metal frame having a first end inserted in said recess and secured to said base, an operating member extending across said frame in substantially parallel relation with said base, means securing each end of said operating member to said frame for limited sidewise sliding movement with relation to said frame, a bellows temperature responsive operating device mounted between one side of said operating member and said first end of said frame, a compression spring between the other side of said operating member and the other end of said frame, said frame forming a support for said parts and holding said parts together against the force of said spring, a screw mounted on said frame for adjusting the force applied by said spring to said operating member, a spring contact arm mounted on said base adjacent said frame, an extension on said operating member projecting outside of said frame into engagement with said contact arm so as to move said contact arm with said bellows, a stationary contact

mounted on said base in position to be engaged by said contact arm, and means for giving said contact arm a snap movement from one position to another.

5 4. A control device comprising a base, a frame secured to said base, a temperature responsive bellows in said frame, an operating member extending across said frame slidably mounted in said frame, a spring in said frame normally holding said operating member against said bellows, said frame forming a support for said parts and holding said parts together against the force of said spring, means including a screw mounted on said frame for adjusting the force applied by said spring to said operating member, 10 a knob on said screw, a flexible contact arm mounted on said base adjacent said supporting frame, an extension on said operating member engaging said contact arm so that said contact arm is moved by said bellows in response to changes in temperature, a projection on said knob, and a member forming an operating connection between said contact arm and said projection so that when said knob is turned to a predetermined position said member is operated by said projection to move said contact arm to a predetermined position.

15 5. A control device comprising a base, a frame secured to said base, a temperature responsive bellows in said frame, an operating member extending across said frame slidably mounted in said frame, a spring in said frame normally holding said operating member against said bellows, said frame forming a support for said parts and holding said parts together against the force of said spring, means including a screw mounted on said frame for adjusting the force applied by 20 said spring to said operating member, a knob on said screw, a flexible contact arm mounted on said base adjacent said supporting frame, an extension on said operating member engaging said contact arm so that said contact arm is moved by said bellows in response to changes in temperature, a projection on said knob, and a member forming an operating connection between said contact arm and said projection so that when said knob is turned to a predetermined position said member is operated by said projection to move said contact arm to a predetermined position.

25 6. A control device comprising a base, a frame secured to said base, a temperature responsive bellows in said frame, an operating member extending across said frame, a spring normally holding said operating member against said bellows, means comprising a screw mounted on said frame for adjusting the force applied by said spring to said operating member, a knob on said screw, a first spring contact arm mounted on said base adjacent said supporting frame, an extension on said operating member engaging said contact arm so that said contact arm is moved by said bellows in response to changes in temperature, a second flexible contact arm mounted on said base adjacent said supporting frame, cooperating contacts on the movable ends of said contact arms, a projection on said knob, and a member mounted on said supporting frame having one end engaging said first contact arm and its other end in the path of movement of said projection so that when said knob is turned to a predetermined position said member is operated to move said first contact arm to its open circuit position and hold it in that position.

30 7. A control device comprising a base, a frame secured to said base, a temperature responsive bellows in said frame, an operating member extending across said frame, a spring normally holding said operating member against said bellows, means comprising a screw mounted on said frame for adjusting the force applied by said spring to said operating member, a knob on said screw, a first spring contact arm mounted on said base adjacent said supporting frame, an extension on said operating member engaging said contact arm so that said contact arm is moved by said bellows in response to changes in temperature, a second flexible contact arm mounted on said base adjacent said supporting frame, cooperating contacts on the movable ends of said contact arms, a permanent magnet mounted on said base adjacent said first contact arm, an armature on said contact arm cooperating with said magnet so as to snap said first contact arm into and out of circuit

closed position, means for adjusting the position of said armature in its attracted position, means for adjusting said second flexible contact arm, a projection on said knob, and a member forming an operating connection between said first contact arm and said projection so that when said knob is turned said member is operated to move said first contact arm to its open circuit position and hold it in that position.

7. A control device comprising a rectangular metal frame, an operating member extending across said frame having its opposite ends slidably mounted in said frame thereby to mount said operating member for limited sliding movement on said frame, one of said ends being elongated to form an operating projection, a bellows temperature responsive operating device mounted between one side of said operating

5 member and one end of said frame, a compression spring between the other side of said operating member and the other end of said frame, said frame forming a support for said parts and holding said parts together against the force of said spring, a seat on said operating member for said spring having a high portion engaged by one side of said spring between the point of engagement of said bellows with said operating member and the other end of said operating member, and a stop on said frame against which said other end of said operating member is held normally by said spring so that upon expansion of said bellows in response to an increase in 10 temperature said operating member is moved about said stop as a pivot, and switching means engaged and operated by said operating projection.

EDGAR H. AYERS.
